COMBINATION DOOR CATCH AND LOCK

Hiram B. Gallinger, Superior, Wis.

Application May 5, 1938, Serial No. 206,216

3 Claims. (Cl. 292—78)

This invention relates to improvements in a combined door catch and lifter, which in many respects is identical with the device shown and described in my copending application Ser. No. 5 148,138, filed June 14, 1937.

The principal object of my present invention is that of providing material improvements both in the functioning of the device as a door catch and lifter, as well as providing a simple, efficient, 10 and convenient door lock in combination with the catch and lifter.

Another material advantage of the instant invention is in the manner of installation of same in respect to both the door opening and the 15 door.

Other objects and advantages of the invention will appear in the following description thereof.

Referring now to the accompanying drawing, forming part of this application, and wherein 20 like reference characters indicate like parts:

Figure 1 is an elevation of the door catch as mounted upon the door and in its normally closed position in respect to the door opening.

Figure 2 is a section on the line 2—2, Figure 1, 25 showing portions of the device in elevation.

Figure 3 is a perspective view of the lock attachment which may be operated in conjunction with the combined lifter and catch.

Figure 4 is a somewhat enlarged perspective 30 view of the lower end of the door catch, designated for cooperation with the lock.

Figure 5 is a somewhat reduced perspective 35 view of the novel form of trigger.

The numeral 1 represents a screen, storm, or 40 other door, as the case may be, for operation within a common door opening, that portion of the door illustrated in the drawing being the free upper edge thereof and which in this instance is designed to engage the edge of the stop 2 within the door jamb 3 of the door.

The catch here illustrated differs only in minor 45 details from that shown in my former application, supra, and it is not deemed essential to describe same in detail, other than to clearly point out these differences, and which will be done hereinafter.

As in my former application, 4 represents the 50 base plate of the catch, which is substantially U-shaped in cross-section and having the outwardly extending somewhat triangularly shaped side walls 5 at the upper extremities of which, as at 6, is the through pin, supporting externally of said side walls 5 the jaw-like housing 7, which oscillates back and forth on said pin when 55 engaged by the cooperating means upon the door

as the latter is opened or closed. The lower outer corners of the side walls 5 are provided with circular openings 11 in which is pivotally supported the inner end of the trigger member 9, it having upturned side flange-like rearwardly extending members 30 formed integral therewith and each of which flanges carries an inwardly projecting arcuate lug 31 which bears against the circumferential edges of the openings 11, thus providing a substantial and durable bearing for said pivotal support of the trigger when assembled.

It will be noted that a slot or gap 32 is formed in the outer wall of each opening 11 for convenient assembly of these cooperating parts as 15 the side flanges of the trigger are externally of the side walls of the base plate 4, and the housing 7 is externally of the trigger when the device is fully assembled. The free end of this trigger extends through a suitable opening 28 in the bottom of the housing 7 for cooperative engagement 20 with the finger projection 14 thereof when the latter engages the roller on the fixed spindle 16. Intermediate of the side members 30 of the trigger and the body portion thereof is formed a 25 hole 12 for hooked engagement with the upper end of the contractile helical spring 13, the opposite end of this spring being hooked about the pin 6 which pivotally supports the housing 7, previously described. The lower end of the housing 30 7 is provided upon its innermost edge with a finger-like projection 14 which cooperates with the trigger 9 in gripping or releasing the roller 15 carried upon the spindle 16 secured to the face of the stop 2 and adjacent the edge thereof. It 35 will be noted by this construction that when the housing 7 is in its outermost extreme position the axial alignment of the spring 13 is slightly at an angle to the line of draft, which would hold the housing normally biased toward its open 40 position ready for the reception of the cooperative attachment carried by the stop, whereas when impinging such attachment on the stop with any degree of force as when the door is swung shut, the housing will be drawn slightly 45 toward the door together with the otherwise free end of the spring beyond that inactive line of stress, and bias the housing toward closed position, thus carrying the door to like position.

It will be noted here that while the general 50 construction of the cooperative parts of the catch are similar to that shown in my former application referred to, the catch itself is turned end for end, or upside down, and mounted upon the door instead of on the door trim, and that in this 55

instance the finger projection 16 carrying the roller 15 is fixed to the stop 2 on the jamb of the door, and which installation is deemed novel. Furthermore the pin or spindle 16 is provided with a base 21 of a width suitable to properly register with the engaging portions of the catch when the door is in closed position and either edge of the base is in direct alignment with the edge of the stop 2, thus providing convenient means 10 as a gage for horizontal placement of the pin 16.

Another novel feature of the instant case is that the free end of the trigger 9 extending beyond the housing 7 is formed with an offset or hump indicated at 22, the same acting as a stop 15 in engaging the lower end of the housing 7 as clearly illustrated in Figure 2 of the drawing thus preventing abnormal wear within the opening 20 in the end of the housing.

Another novel feature of the instant case is 20 that of the lower extremity of the base plate 4 being offset outwardly as at 23 approximately the thickness of the metal of which it is made, and in which offset portion is installed the circular rubber button 24 for abutting contact with the 25 finger 14 of the housing to lessen or cushion the sound of the action of the catch.

Now this lower extremity of the base plate 4 is offset for the reception of the upper forked end 30 of the escutcheon plate 25, the tines of which forked portion will readily straddle the inner projecting end of the button and be housed underneath the projection 23 when slid upwardly beneath same, and a holding screw, not shown, is installed within the hole 26 in the lower extremity 35 of the escutcheon plate. This plate is provided with a rectangularly shaped outwardly stepped portion 27 intermediate of its ends and upon which is pivotally mounted as at 28 the thumb button 29 for adjustment to or from engagement 40 with the free end of the finger 14 when the latter is in closed position against the button 24, whereby to act as a lock for the door, it being understood that when the escutcheon plate 25 is shoved up into place under the stepped portion 23 of 45 the base 4, the extending portion 27 thereof will be in the same plane with the finger 14 to provide for such convenient engagement. By this provision of separable locking means it is obvious that

when these catches are placed on the market it will be optional with the purchaser whether he obtains the combined catch and lifter in its simplest form or in combination with the locking means thus provided, and in so doing the utilitarian properties of the catch are materially augmented.

It is apparent that the same convenient adjustment of the device is provided for the lifting of the door during the closing process by the proper positioning of the pin 16 that occurs in my former application, but in this instance the pin is upon the stop of the jamb instead of on the door as in my former application.

Having thus described my invention, what I claim and desire to secure by Letters Patent, is:

1. A door catch comprising a channel shaped bracket portion, the side walls of which are provided with circular openings therein, a trigger having arcuate lugs thereon for pivotal engagement within the circular openings of said bracket portion, a housing pivoted adjacent one end to said bracket portion, and means for biasing the trigger and housing toward the limit of its movement in either direction. 20

2. A door catch comprising a channel shaped bracket portion having circular openings through the side walls thereof, a trigger having laterally extending surfaces adapted to extend within and bear against the edges of said openings for pivotal engagement therewith, a housing pivoted adjacent one end to said bracket portion, and a spring secured at one end to said bracket portion and at the other end to said trigger for biasing the trigger and housing toward the limit of its movement in one direction. 30

3. In a door catch having a pair of cooperative members each having a pair of spaced parallel walls, one of said members having axially aligned substantially circular openings in the spaced walls thereof, and the other of said members having laterally extending lugs in the spaced walls thereof and adapted to extend within and bear against the edges of said circular openings to form a pivotal joint between said cooperative members. 40
